CLAMP

Filed Oct. 22, 1927

Inventor:
George B. Bosco

Patented July 9, 1929.

1,719,921

UNITED STATES PATENT OFFICE.

GEORGE B. BOSCO, OF CHICAGO, ILLINOIS.

CLAMP.

Application filed October 22, 1927. Serial No. 228,092.

The main objects of this invention are to provide an improved form of clamp adapted for use in connection with a flexible tie element; to provide a clamp having an improved form of collar for receiving a portion of the tie element; to provide improved means for detachably securing the tie element to the collar; to provide an improved form of tool for adjusting the tie element relative to the collar; and to provide a device of this kind which is particularly adapted for use as a form clamp.

An illustrative embodiment of this invention is shown in the accompanying drawing, 15 wherein:—

Figure 1 is a transverse section of a girder mold, to which an improved clamp is applied.

Fig. 2 is a plan of the improved collar.

Fig. 3 is a side elevation of the collar having the ends of a tie element seated therein, the latter being shown in section.

Fig. 4 is a longitudinal section taken on the line 4—4 of Fig. 2, and showing also a wedge in section and a portion of the tie element in elevation.

Fig. 5 is a transverse section, taken on the line 5—5 of Fig. 2, and showing also the tie element in section and a portion of the wedge in elevation.

Fig. 6 is a perspective of the improved collar.

In the specific form herein shown, the invention is applied to a form clamp comprising a tie element and a holding member in 35 the form of a collar secured to the tie element for adjustment longitudinally thereof. Adjustment of the holding member on the tie element is accomplished by means of a separate tool adapted to grip the tie element at 40 a point beyond the collar for pulling the former relative to the latter. Improved means are also provided for detachably securing the tie element and collar together.

In the specific embodiment herein illustrated, the improved clamp is applied to a girder mold suitable for use in concrete construction work and comprising the usual sections 1, battens 2 and spacer blocks 3 suspended from an I-beam 4 by the tie band.

In the form shown, the improved form of clamp comprises a tie element 5, a collar 6 and a tool 7 which is detachable so that one or two of such tools may serve a large number of clamps.

The tie element 5 is preferably in the form of a flexible metal band, the size of which

is dependent upon the character of the mold to which the clamp is applied.

In the embodiment shown, the collar 6 comprises a block having a substantially flat bearing surface 8 on one side thereof, which is adapted to bear against the I-beam 4. Formed on the opposite side of the block, is a seat 9, which is adapted to receive the tie element 5. The seat 9 has an unobstructed mouth 10, so as to permit any portion of the tie band to be placed on the seat, without the necessity of pulling the ends of the band through the collar as has been done heretofore. In the form shown, the seat 9 is sufficiently wide to support two tie bands arranged side by side or two portions of a single band similarly arranged, as shown in Figs. 3 and 5.

Located on respectively opposite sides of the seat 9, is a pair of upstanding lugs 11 and 12, which are slotted to provide keyways 13 and 14 respectively. Formed in the seat 9, is a transverse recess 15, into which the tie band is crimped by the action of a wedge 16, which is adapted to be driven into the keyways 13 and 14.

In the form shown, the tool 7 comprises a shank 17 providing a handle having a jaw 18 provided with a pivot pin 19 on which is mounted a movable jaw 20. The jaw 20 comprises a pair of spaced fingers 21 connected together by a pin 22 which is adapted to coact with the jaw 18 for gripping the tie band. The fingers 21 are recessed adjacent their free ends to provide bearing parts 23, which are adapted to be fulcrumed on the I-beam 4 as shown in Fig. 1. The bearing parts 23 project beyond the pin 22 so as to define a throat adapted to receive a portion of the tie band.

In operation, the tie band 5 is passed through apertures in the section 1 and batten 2 and is then looped around the I-beam 4. One of the improved collars 6 is then placed on top of the I-beam and the end portions of the tie band are inserted in the seat 9 in the manner shown in Figs. 1 and 3. Two of the tools 7 are then applied to the ends of the tie band and the handles 17 are rocked outwardly 100 away from each other to pull the ends of the band outwardly away from the collar. While the tie band is held taut by means of the two tools 7, the wedge 16 is driven into the keyways 13 and 14 for locking the tie band 105 and collar together. The tools 7 may then be removed for use on other parts of the mold.

Although but one specific embodiment of this invention has been herein shown and described, it will be understood that certain details of the construction shown may be altered or omitted without departing from the spirit of this invention as defined by the following claim.

I claim:

10 A clamp comprising a bearing plate having a flat face for engaging the work, a pair of parallel spaced ridges projecting out-

wardly from the opposite face of said plate and arranged to form a seat for a tie element, the space between said ridges forming a keyway for a wedge, and a pair of spaced lugs 15 located on respectively opposite ends of said ridges and having openings arranged in prolongation of said keyway.

Signed at Chicago this 20th day of October 1927.

GEORGE B. BOSCO:
